UNITED STATES PATENT OFFICE.

WILLIAM A. FOX, OF GREELEY, KANSAS.

DESIGN FOR A BADGE.

Application filed January 13, 1928. Serial No. 24,856. Term of patent 7 years.

To all whom it may concern:

Be it known that I, WILLIAM A. Fox, a citizen of the United States, residing at Greeley, in the county of Anderson and State of Kansas, have invented a new, original, and ornamental Design for a Badge, of which the following is a specification, reference being had to the accompanying drawing, forming part thereof.

I claim:—

The ornamental design for a badge, as shown.

WILLIAM A. FOX.
